(57) **CLAIM**

The ornamental design for a street lamp body, as shown and described.

DESCRIPTION

FIG. 1 is a perspective view of the street lamp body showing my new design;

FIG. 2 is an another perspective view of the street lamp body showing my new design;

FIG. 3 is a bottom plan view thereof;

FIG. 4 is a top plan view thereof;

FIG. 5 is a left side elevational view thereof;

FIG. 6 is a right side elevational view thereof;

FIG. 7 is a front elevational view thereof; and,

FIG. 8 is a rear elevational view thereof.

The broken lines are for the purpose of illustrating portions of the street lamp body and form no part of the claimed design.
